UNITED STATES PATENT OFFICE.

WALTHER HIBY, OF SANDAL, NEAR WAKEFIELD, ENGLAND.

APPARATUS FOR CHARGING COKE-OVENs.

1,019,643.

Specification of Letters Patent.

Patented Mar. 5, 1912.

Application filed November 3, 1911. Serial No. 658,327.

To all whom it may concern:

Be it known that I, WALTHER HIBY, Ph.D., a subject of the German Emperor, residing in Sandal, near Wakefield, Yorkshire, England, and whose post-office address is The Cliff, Sandal, near Wakefield, Yorkshire, England, chemist, have invented certain new and useful Improvements in Apparatus for Charging Coke-Ovens, of which the following is a specification.

This invention, which originally formed part of application Serial No. 629890 dated 27th May, 1911, relates to apparatus for carrying out a method of charging a horizontal coke oven by introducing a charge of a length greater than that of the oven chamber.

Owing to the stamped or compressed charge of coal, which is used for charging the horizontal coke oven, being of greater length than the oven chamber the compressed charge is stopped by the other end of the chamber before the charging operation is completed and is broken up so that it is made to fill the empty spaces on each side and is brought into contact with the oven chamber walls. A space is left beneath the door at the bench end to permit passage of as much of the peel of the charging machine as is necessary. When the whole charge is within the chamber the peel can be withdrawn without jamming the charge into the narrower, ram end of the chamber. When the front end of the stamped charge has come against the oven door at the bench end there is a tendency for the part of the charge which has not yet entered the chamber to break up before it is forced into the chamber. It may therefore be advisable to employ side protectors or attach plates to the back of the charging machine. Such plates may enter the chamber with the charge. The back of the charging machine to which the side plates may be attached must be strong enough to sustain the pressure of the coal against it when the peel is withdrawn. Afterward the back and the side plates are themselves withdrawn and the oven doors lowered and luted. In some cases the stamped charge is not so easily broken up as in other cases. It may be advisable therefore to provide the inner face of the door at the bench end with wedge shaped or other projections to aid the breaking up. Or as the charge is being intro-

duced it may be broken up by tools inserted through the top of the oven chamber.

The invention will be described with reference to the accompanying drawings in which—

Figure 1 is a longitudinal vertical section through an oven chamber in a bench of ovens and Fig. 2 a sectional plan thereof.

a is the peel carrying the compressed charge *b* which in the position shown has just been brought to rest against the door *i* at the bench end of the chamber, this door having been incompletely lowered so as to allow of passage of the end of the peel beneath it. The charge being longer than the chamber protrudes from the latter at the ram end and the protruding portion is protected by side plates *c* fixed to the peel, and by the end plate *d* adapted to slide between the side plates. This end plate is fixed to tubes *f* which are guided in a plate *k* carried by a frame work fixed to the peel. The tubes are surrounded by helical springs *e* the ends of which abut against the plates *d* and *k* respectively. The object of these springs is to maintain the plate *d* against the end of the charge while the side plates *c* are being withdrawn together with the peel after the completion of the charging operation. Since the length of plate *c* to be withdrawn varies with the length of the protruding portion of the charge, which may not always be the same, provision is made to adjust the compression of these springs. For this purpose ropes *m* extending through the tubes *f* are attached at one end to the plate *d*. At the other end the ropes are wound up on pulleys adapted to be turned by worm gears on a shaft *n* which is locked from rotation in the opposite direction by a pawl *h*. During the introduction of the charge the springs are held in the desired degree of compression by pawl *h*.

When the front end of the charge has come against the door *i*, the peel *a* is moved forward until the protruding portion at the ram end of the charge has been forced into the chamber, whereupon the peel is withdrawn. During this backward movement springs *e*, after the pawl *h* has been released, expand and maintain plate *d* against the end of the charge until the side plates *c* have been withdrawn from the chamber. The plate *d* is now moved back, if necessary by exerting tension on ropes *m*, sufficiently

to permit of the oven door being lowered, before the peel is completely withdrawn and the doors *i* and *l* are finally closed.

Having thus described the nature of this invention and the best means I know of carrying the same into practical effect, I claim:—

- 5 1. In a machine for charging a horizontal coke oven with a charge of a length greater than that of the oven chamber, the combination of a charging peel adapted to be pushed forward into and withdrawn from the chamber and a framework associated therewith, of side plates attached to the peel for supporting the charge protruding from the oven chamber, an end plate carried by the framework and adapted to slide between the slide plate and means adapted to maintain the end plate against the charge as the peel and the framework are withdrawn from the chamber.
- 10 2. In a machine for charging a horizontal coke oven with a charge of a length greater than that of the oven chamber, the combination of a charging peel adapted to be pushed forward into and withdrawn from the chamber and a framework associated therewith, of side plates attached to the peel for supporting the charge protruding from the oven chamber, a guide plate carried by the framework, tubes each supported by and having one end passing through the guide plates, an end plate fixed to the other ends of the tubes, and a resilient medium interposed between the guide plate and the end plate, and means for adjusting the compression of the said resilient medium.
- 15 3. In a machine for charging a horizontal coke oven with a charge of a length greater than that of the oven chamber, the combination of a charging peel adapted to be pushed forward into and withdrawn from the chamber and a framework associated therewith, of side plates attached to the peel for supporting the charge protruding from the oven chamber, a guide plate carried by the framework, tubes each supported by and having one end passing through the guide plates, an end plate fixed to the other ends of the tubes, and a resilient medium interposed between the guide plate and the end plate as and for the purpose described.
- 20 4. In a machine for charging a horizontal coke oven with a charge of a length greater than that of the oven chamber, the combination of a charging peel adapted to be pushed forward into and withdrawn from the chamber and a framework associated therewith, of side plates attached to the peel for supporting the charge protruding from the oven chamber, a guide plate carried by the framework, tubes each supported by and having one end passing through the guide plates, an end plate fixed to the other ends of the tubes, and a resilient medium interposed between the guide plate and the end plate, and means for adjusting the compression of the said resilient medium.
- 25 5. In a machine for charging a horizontal coke oven with a charge of a length greater than that of the oven chamber, the combination of a charging peel adapted to be pushed forward into and withdrawn from the chamber and a framework associated therewith, of side plates attached to the peel for supporting the charge protruding from the oven chamber, a guide plate carried by the framework, tubes each supported by and having one end passing through the guide plates, an end plate fixed to the other ends of the tubes, and a resilient medium interposed between the guide plate and the end plate, and means for adjusting the compression of the said resilient medium.
- 30 6. In a machine for charging a horizontal coke oven with a charge of a length greater than that of the oven chamber, the combination of a charging peel adapted to be pushed forward into and withdrawn from the chamber and a framework associated therewith, of side plates attached to the peel for supporting the charge protruding from the oven chamber, a guide plate carried by the framework, tubes each supported by and having one end passing through the guide plates, an end plate fixed to the other ends of the tubes, and a resilient medium interposed between the guide plate and the end plate, and means for adjusting the compression of the said resilient medium.
- 35 7. In a machine for charging a horizontal coke oven with a charge of a length greater than that of the oven chamber, the combination of a charging peel adapted to be pushed forward into and withdrawn from the chamber and a framework associated therewith, of side plates attached to the peel for supporting the charge protruding from the oven chamber, a guide plate carried by the framework, tubes each supported by and having one end passing through the guide plates, an end plate fixed to the other ends of the tubes, and a resilient medium interposed between the guide plate and the end plate, and means for adjusting the compression of the said resilient medium.

than that of the oven chamber, the combination of a charging peel adapted to be pushed forward into and withdrawn from the chamber and a framework associated therewith, of side plates attached to the peel for supporting the charge protruding from the oven chamber, a guide plate carried by the framework, tubes each supported by and having one end passing through the guide plates, an end plate fixed to the other ends of the tubes and a helical spring embracing a portion of each tube intermediate of the guide and end plates.
